MEDICAL DIAGNOSTIC CONSOLE

Walter M. Miller, Arlington Heights, and Ronald W. Jodat, Park Ridge, Ill., assignors to Medequip Corporation

Filed Jan. 26, 1970, Ser. No. 21,096

Term of patent 14 years

Int. Cl. D24—02; D6—01

U.S. Cl. D83—1

FIG. 1 is a front elevation of a medical diagnostic console showing our new design;

FIG. 2 is a top plan of the console;

FIG. 3 is an end elevation as seen from the left of FIG. 2;

FIG. 4 is an end elevation as seen from the right of FIG. 2; and

FIG. 5 is a partial section showing the recessed area at the left of FIG. 1 in top plan.

We claim:

The ornamental design for a medical diagnostic console, as shown.
